6 Claims. (Cl. 179—171)

1

This invention relates to wave amplifying systems and in particular to amplifiers employing negative feedback. Specifically the invention relates to a method of preventing self-oscillation in amplifiers of this type.

It is well known that in feedback amplifiers the phase shift which waves of different frequencies undergo during one complete excursion of their travel around the so-called $\mu\beta$ path varies for the different frequencies. It is usually desirable to so design an amplifier that all waves traversing the $\mu\beta$ path over a given range of frequencies undergo a phase shift of substantially 180° or as close thereto as possible. However, even though these conditions are fulfilled, there are always some frequencies outside of the given range for which the phase shift becomes zero, 360° or a multiple thereof, and if the amplifier gain at these frequencies is greater than unity the amplifier may sing or self-oscillate.

It has been suggested that amplifier self-oscillation may be prevented by including within the amplifier circuits, and usually in the feedback path, a network so designed that the waves which tend to produce self-oscillation are highly attenuated thus reducing the gain at these frequencies. However, with my invention self-oscillation at all frequencies is prevented in accordance with a new principle wherein there is produced in addition to the conventional feedback voltage, an additional voltage having such magnitude and phase that the resultant feedback voltage is always displaced 180° with respect to the input voltage. It is immaterial whether the waves which traverse the amplifier are originally impressed thereon from an outside source or are the result of modulation or distortion components developed within the amplifier.

One of the primary purposes of employing negative feedback is to reduce distortion components developed within the amplifier. With the circuit arrangements of my invention the distortion components are most effectively reduced in the frequency range where the deviation from the desired 180° phase shift for one complete excursion around the $\mu\beta$ path is relatively small, that is, of the order of 30° or less. However, since it is at these frequencies that distortion due to hum voltages occur, my circuit arrangement is very effective in reducing this type of distortion. Negative feedback may be applied almost without limit with the result that the hum voltages are practically eliminated and still the amplifier will not oscillate at any frequency.

A primary object of my invention is to provide

2

a stable negative feedback amplifier circuit arrangement which permits high gain over an extremely wide frequency range.

Other objects are:

5 To provide an improved negative feedback amplifier in which the phase difference between an applied input voltage and the net input voltage is substantially zero.

To provide an improved negative feedback amplifier 10 in which distortion components are suppressed over a limited frequency range while the amplifier remains non-oscillatory over an extremely wide frequency range.

To provide a negative feedback amplifier having 15 an overall gain which is proportional only to the forward amplification or μ .

To provide a negative feedback amplifier in 20 which the ratio of the net or effective input voltage with feedback to the applied voltage is constant.

Other objects and features of my invention will 25 become apparent from the following description, the appended claims and the drawings in which

Fig. 1 is a schematic diagram illustrating a preferred embodiment of my invention;

Figs. 2, 3, 4 and 6 are vector diagrams which 30 illustrate the principles of operation of my invention;

Fig. 5 is a polar diagram showing the variation 35 of $\mu\beta$ with frequency; and

Fig. 7 is a schematic diagram illustrating a 40 modification of Fig. 1.

Referring to Fig. 1 the reference character 1 represents a source of voltage which is to be amplified. This source may be of a single frequency or of a plurality of frequencies such as would occur in the output of a voice frequency amplifier. Although the source is illustrated as an alternator it could also be the secondary winding of an input 45 transformer or the output circuit of a vacuum tube amplifier. The reference character 2 represents the impedance of the source 1 and may be, for example, a separate resistance as shown or the plate impedance of an amplifier. The resistance 2 is connected to a junction point 3 and to the grid 4 of an amplifying tube 5. The amplifying tube 5 is illustrated as a triode for simplicity although tetrodes or pentodes could be employed without departing from the principles of my invention. The cathode 6 of the tube 5 is connected to ground through a biasing resistor 7. The anode 8 is connected to a main amplifier 9 illustrated in block form. The internal construction of the amplifier is immaterial in so far as my invention 50 is concerned. It may be a single or a multistage 55

amplifier; if the latter, the various stages may be transformer coupled, resistance-capacity coupled or by any other forms of coupling. Local negative feedback circuits may exist within the amplifier 9 and the phase shift of the amplifier at various frequencies may have any values whatsoever although it would be preferable to employ the best practice and make the phase shift other than the 180° required for negative feedback as small as economically desirable. The amplifying tube 5 is to be considered as part of the amplifier 9 but it is shown separately for purposes of description.

It is understood, of course, that for an unbalanced negative feedback amplifier such as is illustrated in Fig. 1 and where there is substantially zero phase shift in the feedback path, a phase reversal of the voltages for the frequencies within the operating range must occur in order to reduce distortion in accordance with the principles of negative feedback. All of the phase reversal need not take place in the forward or μ path; some of it may be in the feedback or β path.

In amplifiers of the push-pull type the phase reversal may be obtained by crisscrossing the feedback connections from the output to the input circuits in accordance with known practice. The principles of my invention apply equally well to amplifiers of this type.

The necessary power supplies for operation of the amplifier are not shown but are understood to be within the amplifier 9.

The output impedance of the amplifier 9 is illustrated as a resistor 10. A lead 11 connects the output of the amplifier to a load circuit, not shown. From a variable tap 12 on the resistor 10 a negative feedback connection comprising a blocking capacitor 13 and a resistor 14 connects with the junction point 3. As described so far the circuit arrangement constitutes a typical form of feedback amplifier such as may be found in the prior art. The gain of the amplifier at various frequencies may be such that the amplifier will oscillate at some frequency, perhaps not in the range for which the amplifier is designed but at some higher or supersonic frequency at which the phase rotation through the amplifier and feedback path is 0°, 360° or a multiple thereof as above explained.

In accordance with my invention I provide a circuit arrangement, also connected to the junction point 3, which will produce a voltage having the proper magnitude and phase which, when combined with the feedback voltage of the main amplifier 9, will always produce a resultant feedback voltage having a 180° phase displacement with respect to the input voltage. The circuit arrangement is so designed that it will function in the desired manner at any frequency whether this frequency be that of the input voltage or of a distortion voltage developed within the amplifier 9. This circuit arrangement will now be described.

From the junction point 3 a conductor 15 leads to the input grid 16 of amplifying tube 17. The cathode 18 of this tube is connected to ground through a resistor 19. The anode 20 connects to what I have termed a "correlative" amplifier 21, also shown in block form. The tube 17 is to be considered as part of the correlative amplifier but is separately shown for purposes of description. The output of the correlative amplifier is connected to an output impedance shown as a resistor 22. A power supply, not shown, is to be considered as connected to the tubes within the

correlative amplifier. If desired the power supply for both amplifiers 9 and 21 may be common.

The characteristic feature of the correlative amplifier 21 is that it should have substantially identical gain and phase shift characteristics with respect to frequency as does amplifier 9.

The feedback connection comprising capacitor 13 and resistor 14 merely impresses a predetermined fraction of the output voltage developed across resistor 10 onto the input of the main amplifier. This fraction is a scalar quantity, that is, no phase shift is involved. For this reason a similar feedback circuit is not shown in connection with the correlative amplifier 21, any difference in voltage developed on the output resistor 22 due to this omission being compensated for by a suitable adjustment of the contact 23 which selects the required output voltage. On the other hand, if the feedback connection associated with the main amplifier is such that a phase shift occurs in this connection, a corresponding circuit producing the same phase shift should be associated with the correlative amplifier.

There may be cases wherein the construction 25 of the correlative amplifier may be simplified by, for example, the omission of a stage of amplification which involves nothing more than a phase shift of 180°. This phase shift could be compensated for by reversing the connections of a 30 transformer within the amplifier or by other suitable means.

In practice amplifier 9 would usually comprise tubes capable of producing considerably higher output than the tubes in amplifier 21. The 35 variance in power output between amplifiers 9 and 21 is permissible since amplifier 21 merely supplies a voltage of desired magnitude and phase, and the value of this voltage, as determined by the point of contact 23 of conductor 24 on resistor 22, may be the total output voltage of the amplifier, whereas in conventional feedback practice the feedback connection at contact 12 on resistor 10 in the output of amplifier 9 is usually a very small percentage of the output voltage. 40 45 The essential point is that the gain and phase shift characteristics with respect to frequency, from the junction point 3 to the output of amplifiers 9 and 21 respectively, be substantially identical.

50 There is one essential difference between amplifiers 9 and 21 and this pertains to their manner of operation rather than to their structure. The amplifier 9, being in fact a power amplifier is usually operated at high efficiency with the 55 result that the amplifying tubes of said amplifier operate over a large portion of their characteristics, and if their characteristics are not linear, distortion and modulation products are produced. On the other hand it is not necessary that amplifier 21 operate at high efficiency. The tubes of this amplifier should operate only over the linear portion of their characteristics, it being essential that no appreciable amplitude distortion occurs within the amplifier.

60 65 Conductor 15 also connects junction point 3 with the grid 25 of tube 26, this latter tube consisting together with tube 27 a phase mixer 28. The grid 29 of tube 27 is connected with contact 23 of resistor 22 by the conductor 24. 70 The cathodes 30 and 31 of mixer tubes 26 and 27 are connected to ground through resistors 32 and 33 respectively, these resistors being shunted by capacitors 34 and 35. The resistors 32 and 33 develop the desired negative biases for the 75 grids of their respective tubes. Resistors 36 and

37, connected to the anodes 38 and 39 of mixer tubes 26 and 27 respectively, are for isolating the output voltages of these tubes so that they will not interact one with the other but will combine to form a resultant voltage having a value which is the vector sum of the voltages developed by tubes 26 and 27. This resultant voltage which appears at junction point 40 is amplified by the two-stage amplifier 41. Resistance coupling is employed in this amplifier in order that a minimum of phase rotation of voltages will occur therethrough. Two stages are employed in order that the phase of the voltages developed in the output of amplifier 41 will be the same as those applied to the input. The output voltage of amplifier 41 is developed across the resistor 42 in the plate circuit of the second stage. From a variable contact 43 a conductor 44 connects to the junction point 3 through blocking capacitor 45 and resistor 46. The impedance of conductor 15 is assumed to be negligible.

In the above discussion reference has been made to resistors 2, 14 and 46. These resistors permit the use of a single grid on which the combined voltages of three separate sources may be impressed. It is assumed that the resistances are all equal and have values sufficiently great to permit the generation of voltages at each source uninfluenced by the voltages generated at the other two sources. In order to simplify the explanation of my invention I have assumed that the resistances 2, 14 and 46 are all equal so that the three voltage sources each have equal opportunities to influence the net voltage on grid 4, although an increase in any of the resistors can be compensated for by a proportionate increase in the respective source voltage. Moreover, such phase rotation as may exist in practice due to tube and stray capacitance at point 3 to ground is disregarded since this effect has been found negligible over the frequency range in which self-oscillation due to feedback around the main amplifier is possible.

The operation of the circuit of my invention will now be explained by making reference to the vector diagram shown in Fig. 3. In the following discussion of feedback amplifiers, and in particular such amplifiers utilizing my invention, certain mathematical notations and expressions will be used and are here defined. Reference characters found in the definitions refer to Fig. 1.

Notation or Expression	Definition
μ	The voltage gain of the main amplifier without negative feedback. This is a vector quantity, having both amplitude and phase angle.
β	The factor by which the voltage output of an amplifier employing feedback must be multiplied to obtain the voltage which is impressed back onto the input of said amplifier. This, also, is a vector quantity.
ϕ	The phase angle of the product $\mu\beta$. A reference frequency, generally within the useful frequency range of the amplifier, at which ϕ is 180°. A reference frequency at which ϕ is zero or a multiple of 360°.
Mid-frequency. Critical frequency.	
V	A vector representing the net voltage impressed on the grid 4 of amplifier 5 or between point 3 and ground.
V_1	A vector representing the contribution of the externally generated voltage 1 through resistor 2 to the net voltage V .
V_2	A vector representing the contribution of the voltage generated at point 12 through resistor 14 to the net voltage V .
V_3	A vector representing the contribution of the voltage generated at point 43 through resistor 46 to the net voltage V .

In Fig. 2 I have represented by vectors the

system of voltages which add vectorially to produce a net voltage V at the grid 4 of amplifying tube 5. Thus, at any given frequency, there will exist simultaneously the applied or actuating voltage V_1 , the feedback voltage $V_2 = \mu\beta V$, the phase-mixer voltage V_3 and the voltage V which is the vector sum of V_1 , V_2 and V_3 . That is,

$$V = V_1 + V_2 + V_3$$

- 10 The significance of V_3 in this equation may be illustrated by reference to a conventional feedback system operating without benefit of V_3 . The vector diagram of such a system is shown in Fig. 3, where the amplitude and phase angle of $\mu\beta$ is the same as for Fig. 2. It is a well-known fact that if ϕ is 0° (or 360°) and the ratio of V_2 to V is greater than unity, the conventional feedback system will become unstable; that is, it may self-oscillate. One purpose of my invention is to avoid this unstable operation or self oscillation in a negative feedback amplifier.

Again referring to Fig. 2 in which the magnitude and phase angle of $\mu\beta$ is the same as for Fig. 3, a stable condition of operation may be achieved by developing a voltage represented by vector V_3 having a magnitude and phase angle for all frequencies such that, when added to voltage vector V_2 , a resulting or net feedback voltage vector V_4 will be produced which will always be substantially 180° from V_1 and have an amplitude which is a fixed fraction of the amplitude of V_1 for all frequencies. Such a system cannot oscillate, since for any value of ϕ the net feedback voltage will always have substantially the amplitude and phase angle as that corresponding to operation at mid-frequency at which ϕ equals 180°.

- 40 The manner in which the voltage represented by vector V_3 is developed will now be explained by referring to the vector diagram of Fig. 4. This figure represents the phase and amplitude relations between the voltages impressed upon the inputs of the phase mixer 28, the voltages developed therein, and the resultant or output voltage of the phase mixer. The final (net) voltage, represented by vector V and impressed on the grid 4 of tube 5, is also impressed upon the grid 16 of amplifying tube 17 and upon the grid 25 of tube 26, the latter constituting one element of the phase mixer 28. The voltage impressed upon grid 16 appears, after amplification in the correlative amplifier, across resistor 22. This voltage will have a phase relation identical with that appearing across resistor 10 in the output of the main amplifier 9, it being remembered that the correlative amplifier is so designed that its gain and phase shift-frequency characteristic is substantially the same as that of the main amplifier. The contact 23 selects the desired magnitude of this voltage which is impressed on the grid 29 of tube 27, the latter constituting the second element of the phase mixer 28. This voltage is represented by vector V_c on Fig. 4.
- 50 60 65 70 75 776 The there are now two voltages, V and V_c , operating on the phase mixer. The voltage V is amplified and reversed in phase by the tube 26 and appears in the output circuit thereof between the point 40 and ground. This amplified voltage is represented by vector V_5 in Fig. 4. Voltage V_c is amplified and reversed in phase by the tube 27 and also appears in the tube output circuit between the point 40 and ground. This amplified voltage is represented by vector V_6 . The resultant of the voltage vectors V_5 and V_6 is V_3' .

The phase angle of V_3' is dependent on the magnitude of V_c which in turn is determined by the position of contact 23 on resistor 22. The magnitude of V_3' is also dependent on the position of contact 23. This latter dependency is of particular importance for the condition where ϕ equals 180° as will be seen when the preferred circuit adjustments are described.

The voltage represented by V_3' is amplified by the amplifier 41 and appears without change of phase across resistor 42. Contact 43 determines the magnitude of the voltage which is impressed back on the grid 4 of tube 5, and has already been defined as vector V_3 .

To facilitate the desired adjustment of contact 23 on resistor 22 it is preferable to make said adjustment when the applied voltage from source 1 has the frequency for which $\phi=180^\circ$, that is, mid-frequency. This frequency may be obtained by plotting a polar diagram of the magnitude and phase angle of $\mu\beta$ over a range of frequencies sufficiently great to include the mid-frequency. Since, when employing this frequency, the voltage V_3 should be zero, it is only necessary to place a suitable voltmeter across the output of the phase mixer and make the proper adjustment of contact 23 until this voltmeter reads zero. This follows from the fact that $\phi=180^\circ$ and, in Fig. 4, V_c is in phase opposition to V_3 .

The desired adjustment of contact 43 on resistor 42 may most readily be made by applying a voltage from source 1 having a frequency for which the phase angle ϕ is zero, that is, a critical frequency. It is preferable that the particular critical frequency selected be the next higher frequency above the mid-frequency. When employing this frequency, the voltage V_3 should be of such magnitude as to reduce the output of the main amplifier to that value which corresponds to μV_1 (for the critical frequency) divided by the numerical value of $1-\mu\beta$ at mid-frequency. This follows from the fact that when using the correlative amplifier and phase mixer in connection with a feedback amplifier in accordance with my invention, the net gain of the feedback amplifier should be μ (measured at a particular frequency) divided by the numerical value of $1-\mu\beta$ measured at mid-frequency. A suitable voltmeter may be placed across resistor 10 and the position of contact 43 varied until the output voltage corresponds to that indicated above.

The value of this voltage can also be obtained by employing data obtained from the above described polar diagram provided the diagram is extended to include a frequency for which $\phi=0^\circ$. This will be clear by referring to Fig. 5 in which the curve represents the locus of $\mu\beta$ for a range of frequencies sufficient to include a frequency for which $\phi=180^\circ$ and a frequency for which $\phi=0^\circ$.

When adjusting the contact 23 on resistor 22 to obtain zero output from the phase mixer as above described, a given voltage V_1 at the frequency for which $\phi=180^\circ$ is applied between junction point 3 and ground. This voltage is not applied directly but is the result of a given voltage from source 1 and the known resistance values of resistors 2, 14, and 46. This given voltage V_1 may be assumed to be unity. When the output of the phase mixer is zero the output voltage of amplifier 9, as measured across resistor 10 or between the contact 12 and ground, is noted.

When adjusting the position of contact 43 on resistor 42 to produce the required operating con-

ditions, the frequency of source 1 is changed to the value for which $\phi=0^\circ$. From the diagram of Fig. 5 the ratio of the scalar value of $\mu\beta$ for $\phi=0^\circ$ to the scalar value of $\mu\beta$ for $\phi=180^\circ$ is obtained.

5 With the voltage V_1 at the frequency for which $\phi=0^\circ$ the same as that for which $\phi=180^\circ$, contact 43 is adjusted until the ratio of the output voltage of amplifier 9 to the output voltage previously noted is equal to the ratio of scalar values above mentioned. In Fig. 5 this ratio is 0.7.

10 Further analysis of the vector diagram of Fig. 2 discloses an interesting fact regarding the amplification obtainable with the feedback circuits of my invention. With feedback circuits as used heretofore, the net amplification is

$$\frac{\mu}{1-\mu\beta}$$

that is, the output voltage is

$$\frac{\mu}{1-\mu\beta} V$$

20 The vector relations for this circuit are shown in Fig. 3. It is apparent that V will not remain constant either in position or in magnitude for different frequencies, whereas in accordance with my invention the vector V remains constant both in position and magnitude for any value of $\mu\beta$ as shown by Fig. 2. The significance of this fact is that the gain and phase-frequency characteristic of the conventional negative feedback amplifier is altered by the feedback circuit, whereas, in accordance with my invention, the gain and phase-frequency characteristic is unchanged by the feedback circuit. In the latter instance, the gain is reduced by a constant proportion corresponding to the degree of feedback established at mid-frequency and the output voltage is μV .

25 So far nothing has been said regarding distortion voltages which may be developed in the main amplifier. It will now be shown that these distortion voltages will not produce self-oscillation and that without change in adjustments for the correcting voltage V_3 the phase of the final distortion voltages will always coincide with the 30 phase of the distortion voltages as first applied to the grid 4 of tube 5.

35 The distortion voltages first appear within the circuits of the main amplifier and are impressed upon the output resistor 10. A portion of these 40 voltages, depending on the position of contact 12, are fed back onto the grid 4. The voltages thus impressed on grid 4 will set up a system of voltage vectors in exactly the same manner as if the distortion voltages originated in the source 45 1. The operation of the correlative amplifier and the phase mixer circuits produce the required correcting voltage and a vector diagram of the various voltages throughout the circuit resulting from the distortion components will be identical 50 with that of Fig. 2, where V_1 represents the contribution of the distortion voltage appearing in the amplifier output through resistor 14 to the net voltage V .

55 In order to show the extent to which distortion is suppressed in the circuit of my invention reference is now made to the vector diagram of Fig. 6. In this diagram I have reproduced the vectors of Fig. 2 without change in nomenclature except to substitute for V the reference character D (for distortion).

60 In Fig. 6 the vector D_1 represents the distortion voltage at an assumed frequency as it first appears on, or is applied to, the input of the tube 5 at the junction point 3, it being remembered that distortion voltages are first generated

within the amplifier 9. In accordance with the explanation already given of the operation of the correlative amplifier and phase mixer, the result of this applied distortion voltage will be a feedback voltage D_2 and a phase mixer voltage D_3 resulting in a net voltage D . It is here assumed, for simplicity, that β has no inherent phase angle, so that for the distortion frequency assumed the phase angle ϕ_1 is the phase angle of μ .

Vectors D_1 and D_2 , although representing voltages between the junction point 3 and ground, are directly proportional to, and therefore representative of, the distortion voltage first appearing across output resistor 10 without feedback and to this voltage as modified by feedback, respectively. The resultant distortion voltage is therefore proportional to the vector sum of D_1 and D_2 or D' . It will be seen, therefore, that in accordance with my invention the distortion has been changed in the ratio of vector D_1 to vector D' .

If the frequency of the distortion voltage developed within the amplifier is such that the phase angle of $\mu\beta=\phi_2$ and the feedback voltage is represented by D_2' , the resultant distortion voltage is proportional to vector D'' , that is, the sum of vectors D_1 and D_2' . In this case it will be evident that the final distortion with feedback is considerably greater than the distortion without feedback. In other words, in so far as distortion components for frequencies having considerable phase shifts are concerned, there may be no reduction in distortion due to feedback.

It may be well to point out that the vectors D_2 and D_2' have been drawn such that they have the same magnitude as vector D_4 . Usually attenuation accompanies increased phase shift with the result that in an actual amplifier the voltage vector D_2 would be somewhat smaller than that of D_3 , and the voltage represented by vector D_2' would be smaller than that of voltage vector D_2 . If this were the case, the final distortion voltage vector D'' would not be as great as that shown in Fig. 4. In any case, however, it is only the distortion components having small phase shifts which are considerably reduced by the circuit arrangements of my invention.

As shown in Fig. 6, if the feedback voltage maintains a constant value regardless of frequency, the locus of the ends of the vectors representative of the final distortion is a circle shown by the dotted circle 47 having its center at the extremity of vector D_1 , and having a radius equal to D_2 .

One very objectionable distortion component encountered in practice is due to the use of alternating current for heating the cathodes of the vacuum tube amplifiers and to the ripples in the rectified voltages for supplying power to the tube anodes. These components usually occur at frequencies which are subject to only a small phase shift. It will therefore be seen that the circuits of my invention are particularly valuable in reducing distortion components due to hum because an unusually great amount of feedback may be employed for reducing these distortion components without self-oscillation.

It may be desirable to more completely suppress a distortion component at some particular frequency. This may be done by inserting a phase shifting network in the amplifier circuits such that the phase angle of $\mu\beta$ will be substantially 180° at the desired frequency.

Another advantage of the circuit arrangements of my invention is that they may be applied to

any existing amplifier whose operation it is desired to improve. All that is required is that a polar diagram showing the variation of $\mu\beta$ with frequency be made of the existing amplifier, and a correlative amplifier be constructed which has a $\mu\beta$ -frequency characteristic represented by substantially the same diagram. The correlative amplifier 21, the phase mixer 28 and the amplifier 41 constitute an active network which may be connected to the circuits of the main amplifier at a single point, namely the junction point 3. There is no need of making any change to the amplifier circuits whose performance is to be improved other than, for example, the adding of isolation resistors such as resistors 2 and 14, and these may already be part of said amplifier.

Another manner in which the applied voltage, the feedback voltage, and the phase mixer voltage may be caused to act independently is shown in Fig. 7. In this figure I have dispensed with the isolating resistors 14 and 46 and have submitted a multigrid tube 48 for the triode 5 of Fig. 1. Resistor 2 may now have a relatively low value without affecting the operation of my invention. I have illustrated the tube 48 as having three control grids, 49, 50 and 51, one for each of the voltages which is to independently exert control on the anode current of the amplifying tube 48. A voltage representing the resultant of the combined effects of these voltages will be found to exist across the resistor 52 connected between the cathode 53 and ground. The desired potential to be applied to tubes 17 and 26 may be selected by contacts 54 and 55 respectively on resistor 52. It will be noticed that no phase change has been assumed between the voltages applied to the grids of the tube 48 and those voltages obtained from the resistor 52. This will be substantially true for the range of frequencies of greater interest. Resistors 56 and 57 are grid leaks for establishing an appropriate D. C. potential on the grids 51 and 49 of the tube 48.

Other modifications of my invention will occur to those skilled in the art and it is to be understood that the illustrations given in this specification are given by way of example only and not as limiting the scope of the invention as set forth in the objects and the appended claims.

In certain of the claims I have used the expression vector-frequency characteristic. A vector-frequency characteristic is understood to be the vector quotient of the output voltage divided by the applied input voltage over a frequency range. The vector-frequency characteristic takes account of the phase angle relationship as well as the amplitude relationship between the output voltage and applied input voltage.

What is claimed is:

1. In combination, a feedback amplifier having an input circuit and an output circuit and a feedback connection therebetween, a correlative amplifier having an input circuit and an output circuit, and a phase mixer having two input circuits and an output circuit, means connecting the input circuits of said feedback and correlative amplifiers and one of the input circuits of said phase mixer together at a common point, means connecting the output circuit of said correlative amplifier to the other input circuit of said phase mixer, means connecting the output of said phase mixer to said first connecting means, a source of potential applied to said common point, and a load circuit connected to the output circuit of said feedback amplifier.
2. The combination of claim 1 in combination

11

with means for adjusting the output voltage of said phase mixer to zero for a frequency of said source of potential for which phase shift through said feedback amplifier is 180°.

3. In combination, a feedback amplifier having an input and an output circuit and a feedback connection therebetween, a correlative amplifier having an input and an output circuit, a phase mixer having input and output circuits, means connecting the input circuits of the correlative amplifier and phase mixer to the input circuit of the feedback amplifier, means connecting the output circuit of the correlative amplifier to the input circuit of the phase mixer, means connecting the output circuit of the phase mixer to the input circuit of the feedback amplifier, a source of applied voltage having a range of frequencies connected to the input circuit of the feedback amplifier and voltage adjusting means for adjusting the magnitude and phase of the voltage developed by the phase mixer to a value such that the final voltage effective in the input circuit of the feedback amplifier will have the same phase as the applied voltage from said source over said range of frequencies.

4. The combination of claim 3 in which the input circuit of the feedback amplifier comprises a multigrid tube, the applied voltage being connected to a grid of said tube, said feedback connection being connected to a grid of said tube, and the output of the phase mixer being connected to a grid of said tube.

5. A negative feedback amplifier comprising an input circuit and an output circuit and a feedback connection therebetween for providing a feedback voltage and an additional circuit con-

12

nected across said input circuit for producing an additional voltage which when combined with said feedback voltage will produce negative feedback over a wide band of frequencies, said additional circuit comprising a phase mixer circuit having two input circuits and an output circuit and a correlative amplifier having an input and output circuit, said input circuit of said correlative amplifier and one of said input circuits of said phase mixer being connected to the input of said amplifier, the output circuit of said correlative amplifier being connected to the other input circuit of said phase mixer, and said output circuit of said phase mixer being connected to said input circuit of said amplifier.

6. A negative feedback amplifier according to claim 5, further comprising adjustable means connecting said correlative amplifier to one of the input circuits of said phase mixer for adjusting the magnitude and phase of the voltage applied thereto such that the output voltage of said phase mixer is zero for frequencies for which the phase shift of said feedback voltage is 180°.
